T. F. CHEEK

RECORD CONTROLLED MUSICAL INSTRUMENT

Filed May 7, 1921.

UNITED STATES PATENT OFFICE.

TOLBERT F. CHEEK, OF NEW YORK, N. Y., ASSIGNOR, BY MESNE ASSIGNMENTS, TO WELTE-MIGNON CORPORATION, OF NEW YORK, N. Y., A CORPORATION OF DELAWARE.

RECORD-CONTROLLED MUSICAL INSTRUMENT.

Application filed May 7, 1921. Serial No. 467,649.

This invention relates to a piano playing mechanism comprising pressure controlling and maintaining means of such nature that the pressure to which the striker pneumatics are subjected may be so regulated in the operation of the mechanism as to produce the various dynamic effects called for by an artistic rendition of the composition being played. It more especially relates to improvements in mechanisms whereby the dynamic effects may be controlled either manually or under control of a suitably prepared record, at will; and consists in certain novel combinations and correlations of elements substantially as hereinafter described and particularly set forth in the appended claims.

Mechanism of the class to which this invention relates have been provided with main sources of power and striker actions and with regulating valves arranged between the main sources of power and the striker actions for controlling the degree of suction or pressure to which the striker actions are subjected. These mechanisms also have included means to move the regulating valves in accord with the pneumatic tension to be produced at any one time in the striker actions and means whereby this tension is maintained whether one or many notes be simultaneously sounded at such time. One of the important purposes of the present invention is to provide mechanisms of the class stated with improved means of simple and inexpensive nature whereby movements of the regulating means may be instantaneously effected under control of an operator with practically no effort on the part of the operator.

In one type of mechanisms of the class to which the present invention relates, the means to set the regulating valve in accord with the pneumatic tension to be produced at any one time in the striker action, has been of a nature such that the regulating valve may be set in any one of a number of different positions, under control of a perforated note sheet or other appropriate record, which means co-operate with pressure maintaining means, such as hereinbefore referred to, to enable the mechanism to reproduce with accuracy the various dynamic effects called for by an artistic rendition of the piece being played. Another of the im-

portant purposes of the invention is to provide mechanisms of the particular type last referred to, with humanly operable mechanism so correlated with the mechanism for setting the valve under control of a record that said mechanisms may be operated together or individually, at will—in other words, to so correlate the mechanism which moves the valve under control of a record and the mechanism for moving the valve under control of the operator that either mechanism may be operated without rendering the other inoperative at the same time, or either may be operated independent of the other, at will.

These several purposes of the invention are well accomplished by the construction illustrated in the accompanying drawings, wherein like letter of reference denote corresponding parts in both figures.

In said drawings:—

Figure 1 is a diagrammatic representation of one form of player mechanism embodying the invention with parts thereof in section, and showing one of the striker pneumatics with its operating valve in the wind chest in a position at right angles to corresponding pneumatics and valves shown in other parts of the figure.

Figure 2 is a detail view of the valve block and its valves, and manually operable buttons for manually controlling the operation of parts which in turn control the operation of parts which in turn control the movements of the regulating valves.

The striker action, which may be of any suitable construction, is divided to provide a plurality of independently operable sections, here exemplified by showing it divided into a bass section A and a treble section A¹, the division being formed by a partition a² arranged intermediate the length of the main conduit in said chest, whereby said conduit is separated into sections a, a¹, for the respective sections of the action. This action is provided with a suitable strike pneumatic for each note, one of said strike pneumatics being shown in Fig. 1 and designated a³ in said figure. These pneumatics have communication with the corresponding section a, a¹ of the main wind conduit in the action through suitable ports and passages controlled by valvular members a⁴ which themselves are controlled from a tracker B pro-

vided with ducts *b* through which it has communication with the striker action. The striker action illustrated is well known and needs no further description, and, moreover, any suitable form of striker action may be employed.

The mechanism also includes a main source of power, the one here illustrated including as usual a feeder *C* and a sustaining pneumatic *D*. This main source of power has communication with the several sections *a* *a'* of the main wind channel in the striker action; but its communication therewith is regulated by a valve 10 for each of said sections, and the action of each of these regulating valves in turn is controlled by suitable expression and pressure maintaining mechanisms, such as those presently described. In general, it may be stated that the mechanisms which act upon each regulating valve to control the tension of the air in the corresponding sections *a* or *a'* of the main wind channel essentially include a suitable expression member, as pneumatic 11 for example, and a suitable regulating member as pneumatic 12 for example, and appropriate connections whereby the regulating valve will be moved under control of the expression member to vary the tension of the air in the corresponding section of the main wind channel and will then be under control of the regulating member which will act to maintain said tension regardless of the number of striker pneumatics operated simultaneously.

There are many known forms of mechanisms including regulating valves and pressure controlling and maintaining means suitably correlated for the purposes of the present invention and likewise there are many suitable constructions of striker actions which may be employed in the practical embodiment of the present invention. Among these are the constructions shown in patent to Welte and Bockisch, issued November 7, 1911, Number 1,008,291; and others not necessary herein to recite, but each of which as stated includes some form of regulating valve and pressure controlling and maintaining means, correlated to move the valve to vary the tension of the air in the main wind channel and to maintain said tension whether only one is operated at one time or more striker pneumatics are operated simultaneously, and to any one of which forms of mechanism the present invention may be applied without departing from its spirit.

In the form herein illustrated, for exemplary purposes only, each expression pneumatic 11 has its movable board 11^a provided with a flat spring 13 which is secured thereto at one end and has its other end connected by a rod 14 with the movable board 12^a of the regulating pneumatic 12,

which movable board in turn is connected to the regulating valve 10 by a rod 15, the said valve being arranged to control a port 16 intermediate the ends of a channel, one end, 17, of which channel is in communication with the main source of power through a duct 18 and the other end, 19, of which is in communication with the corresponding section *a* or *a'* of the main wind channel in the striker action through a duct 20. This form exemplifies among other things a construction in which there is a connection between the controlling means and the pressure maintaining means for transmitting action of the former to the latter and which connection includes a spring whereby there is provided a variable tension device by which the action of the regulator and consequent pressures of the main source of power with reference to the striker pneumatics are varied. It should be understood that in practice the regulator valves 10 are never entirely closed and that when the parts are in the position shown the tension of the air in section *a* *a'* of the main wind channel is such as to play pianissimo. At this time the tension of the spring 13 is weak because the expression pneumatic 11 is expanded. Accordingly, the regulator valve 10 is subjected to weak spring tension which, however acts thereon, through the rod 14, regulating pneumatic 12 and rod 15 to maintain the tension of the air in the corresponding section *a* or *a'* of the main wind channel regardless of the number of striker pneumatics operated simultaneously, in manner well known in the art. If a stronger tone be desired, the particular expression pneumatic 11 corresponding to the notes to be played with such stronger tone is collapsed, thus increasing the tension of the corresponding spring 13. This, as is well understood, increases the tension of the air in the corresponding section *a* or *a'* of the main wind channel and this increased tension is maintained, as before, by the action of the spring 13 and regulator bellows 12.

I have provided improved means for expanding or collapsing the expression members 11 under control of the operator. This means comprises pneumatics 21 whose movable boards 21^a are suitably connected to the movable boards 11^a of the pneumatics 11 respectively and are respectively controllable humanly as by manually operable air controlling buttons 22 and suitable connections between the buttons and the pneumatics 21. The preferred connection between each button 22 and the corresponding pneumatic 21 preferably comprises a duct 23, whose mouth is arranged in a valve board 24, having a spring valve 25 for closing said mouth, and whose discharge end is in a chamber 26 in a valve box, the latter

also having chambers 27 and 28, a port 30 through which these chambers communicate with each other, an atmospheric port 31 to the chamber 28, a port 32 between the chamber 28 and the pneumatic 21, a valvular member 33 in the chamber 28, adapted to close ports 30 and 31 alternately and provided with a stem 34 connected at one end to a membrane 35 which separates the chambers 26 and 27 from each other, and a duct 27^a through which the chamber 27 has communication with the main source of power. It will be noted that when either manually operable valve 25 is opened by pressing its button 22 downward air at atmospheric pressure will be admitted to corresponding chamber 26 through corresponding duct 23, thereby moving the corresponding valvular member 33 to position in which it closes the corresponding atmospheric duct 31 and opens the corresponding suction duct 30, thereby opening communication between the corresponding pneumatic 21 and the main source of power. This pneumatic 21 being thus collapsed similarly collapses the corresponding expression pneumatic 11, and increases the tension of the spring 13 connected to said expression pneumatic, thereby as already stated, increasing the tension of the air in the corresponding section *a* or *a'* of the main wind channel. When the button 22 is released, the tension of the spring valve 25 acts to close the duct 23 and force the button back to its former position. The admission of atmospheric air to chamber 26 being thus cut off, the valvular member 33 returns to its former position in which it closes the suction port 30 and opens the atmospheric port 31, this return being expedited, if necessary, by a bleed hole between chambers 26 and 27 and also by a spring 36 connected to the valve. Air at atmospheric pressure is now admitted to the pneumatic 21 through the port 31, chamber 28 and port 32 causing expansion of the corresponding expression pneumatics 11 by their respective springs, as well understood.

The humanly controlled means herein described for expanding and collapsing the expression pneumatics 11 is well adapted for use in a mechanism which also comprises means for expanding and collapsing said pneumatics under control of a record, one such means being shown in the drawing.

The illustrated means is identical with that shown and described in the Welte and Bockisch Patent No. 1,008,291, hereinbefore referred to, and comprises an expression action E for each pneumatic 11, and connections between the tracker B and the respective expression actions and between the latter and the main source of power and expression pneumatics 11, and also comprising stop pneumatics 40 and connections between the latter and the expression actions. As

the particular illustrated expression actions are known in the art a general description thereof will suffice. Each includes a main wind channel 41 which has communication with the main source of power through a channel 42 and the hereinbefore referred to channel-end 17 and duct 18. Each also includes a series of chambers 43-48, which have communication with the tracker B, through ducts 49 and are separated from the corresponding wind channel 41 by membranes 50. Each further includes a series of chambers, 51-56, each having a suction port 57 and an atmospheric port 58, and provided with a valve 59 whose stem 80 is connected to the corresponding membrane 50, each valve serving to open the corresponding suction port and close the corresponding atmospheric port when the corresponding duct 49 is opened to admit air at atmospheric pressure to the corresponding chamber 43-48, and to close the suction port and open the atmospheric port when the corresponding duct 49 is closed. As well understood in the art. The chamber 51 of each expression action is connected with the corresponding expression pneumatic 11 by a duct 60, and the valve 59 in each of these chambers has its stem connected to a second membrane 61 arranged in a chamber 62 whose portion above the membrane is connected with the chamber 51 by a channel 63 and whose portion below the membrane is connected with the next chamber 52, by a channel 64. Each chamber 52 is connected by a duct 65 with a small pneumatic 66 whose movable board is provided with a valve 67 for opening a port 68 to quickly vent the corresponding expression pneumatic 11 when air at atmospheric pressure is admitted to the chamber 44. Each chamber 53 is connected by a duct 69 with the corresponding expression pneumatic 11 and the stem of its valve is connected to a second membrane 70 arranged in a chamber 71 whose portion above the membrane is connected to chamber 53 by a channel 72 and whose portion below the membrane is connected to the adjacent chamber 54 by a channel 73. The duct 69 is of lesser diameter than the duct 60 so that it exerts lesser pulling force on its pneumatic 11 in a given length of time. Each chamber 55 is connected with the corresponding stop pneumatic 40 by a duct 74 and the stem of its valve is connected to a membrane 75, arranged in a chamber 76 whose portion above the membrane is connected to the chamber 55 by a duct 77 and whose portion below the membrane is connected to the adjacent chamber, 56, by a duct 78.

The operation of these actions on their respective expression pneumatics 11 is well known and need not be described in detail.

It will be noted that this particular em-

bodiment of the invention, as thus far described, comprises in addition to the means for collapsing and expanding the expression pneumatic under control of a record, a separate, manually controllable, means of simple and positive action connected to said pneumatic and capable of expanding and collapsing the same without requiring that the record controlled means be out of operative relation with said pneumatic while the manually controlled means are in use. In other words, the two means are operatively independent of each other. It, therefore, becomes practicable not only to employ records which are unprovided with special expression perforations, in which event the expression is controlled solely by the manually controllable means, but also to employ records which have expression perforations for controlling the expression actions. In the latter event, the expression pneumatic may be operated under control of the record wholly, or it may be operated partly under control of the record and partly under manual control, thereby enabling the operator to change or modify the expression brought about under control of the record solely.

It is preferred, when humanly controlled means are embodied in a mechanism which also has record controlled means for controlling the expression controlling means, that the humanly controlled means be of less power than the expression controlling means. In the illustrated embodiment of the invention each manually controlled pneumatic 21 is smaller than the expression controlling pneumatic 11 to which it is connected. Accordingly, it will be noted that it may be operated in conjunction with the expression action connected with said pneumatic 11 to temporarily change the action of the pneumatic 11 on the regulating valve 10 as compared with the action brought about under control of the record exclusively, the change effected being a further opening of the valve, without essentially opening it to its extreme limit, as would be the case if the power of the pneumatic 21 were such that it would fully collapse the pneumatic 11, even when the latter be in full expanded position, whenever it (the pneumatic 21) be opened.

It is also preferred to provide humanly controllable means to soften as well as humanly controlled means for strengthening the tones brought about under the action of the record controlled means, temporarily. In the illustrated embodiment of the invention, this is brought about by reducing the tension of the air in the expression pneumatic. Any means for this purpose, embodying an appropriate vent and humanly operable connections thereto may be employed but I prefer to utilize the venting pneumatics 66 and accordingly have shown

the particular tracker ducts 49 which lead to the chamber 50 as being tapped by ducts 80 whose mouths are arranged in the valve board 24 and are opened and closed by spring valves 81 under control of manually operable buttons 82. Moreover, the expression pneumatics 11 may be manually controlled to produce tones of greater strength than pianissimo, for example, by increasing the tension of the air under manual control as well as under control of the record. In such case, it is advisable to utilize the duct 69 for both manual and record control of the pneumatic 11.

In this particular exemplification of the invention the valve board 24 is mounted on the part 83 of the piano casing immediately in advance of the piano keys 84, this being a convenient and usual arrangement of manual controlled buttons for controlling expression in piano playing mechanisms. Moreover, I have shown the striker pneumatics 11 as operating upon the exposed faces of the keys, through pivoted striker arms 85 connected to the movable boards of the striker pneumatics. This is customary when the playing mechanism is embodied in a casing outside of the piano casing-cabinet players, so called—for example; but it is quite obvious that this is merely exemplary and that the playing mechanism may, and in actual practice, in many or the majority of cases will be arranged in the interiors of the piano cases and will act either upon the inner ends of the keys or upon appropriate parts of the piano action, as preferred.

Moreover, while I have illustrated and described an expression action—or expression actions—operating under control of a record to control the pneumatic tensions within the expression pneumatics, I would have it understood that it will not be a departure from the spirit of the invention to provide means controllable by the operator of the instrument for varying the pneumatic tensions within the expression pneumatics 11, and also within the stop pneumatics, if the latter be employed. Such humanly controllable means may be in addition to, or employed as a substitute for, the tracker ducts 49 as preferred. Many humanly controllable ways for controlling the tensions within the expression pneumatics will readily suggest themselves to those skilled in the art and as it is within the spirit of the invention to employ any of the same, it is considered to be unnecessary to describe or illustrate any of the same in detail. It may be mentioned, however, that a simple and practicable way for humanly operating the particular expression action shown, would involve merely the use of a series of ducts, corresponding to the ducts 49, connected to the chambers 43—48, respectively, with ap-

properiate manually operable buttons and valves, (like the buttons and valves 25 shown for controlling the valves which control the pneumatics 21 for example): or if 5 the expression valves of the action illustrated are to be under either manual and tracker control, at will, the duct 49 may be tapped by ducts, (similar to the ducts 80) controlled for example, by manually 10 operable valves similar to the valves 25 and 81. However, as already stated, different ways of humanly controlling the pneumatic tensions within the expression pneumatics will readily suggest themselves in accordance 15 with the particular construction of expression action with which such means are to be associated or with the particular construction of expression action with which such means are to be associated, or with the 20 particular changes of pneumatic tension in the expression pneumatics which are to be effected thereby.

Again, it will be understood that although the mechanism herein illustrated 25 and described has been illustrated for use in a system operating on the suction principle, it would not be a departure from the spirit of the invention to embody it in a system operating on the compression principle. The changes necessary to adapt the mechanism for operation when air having 30 a pressure greater than the atmosphere is to be used in lieu of air having a pressure less than atmospheric, are well understood by 35 those skilled in the art and need not be illustrated herein.

Having thus described the invention what I believe to be new and desire to secure by Letters Patent is:—

- 40 1. In a piano playing mechanism, striker pneumatics, a source of power for actuating the striker pneumatics, expression controlling means to control the degree of pressure at the striker pneumatics in accordance, with the setting of said expression controlling means for high, low or intermediate pressures respectively, pressure maintaining means for maintaining substantial uniformity of the pressure for which the pressure controlling means may be set, whatever 45 number of striker pneumatics be simultaneously operated, a spring connecting said expression controlling means with said maintaining means, to transmit the action of the former to the latter, an operating pneumatic connected to the expression controlling means to operate the same, and humanly operable means connected to the operating pneumatic to control the same.
- 50 2. In a piano playing mechanism, striker pneumatics, a source of power for actuating the striker pneumatics, means for controlling the air supply, located between the striker pneumatics and said source of power, 55 a regulating pneumatic in free communica-
- 56 tion with the striker pneumatics and connected with and arranged to move the air controlling means to maintain substantial uniformity of pressure at the striker pneumatics, whether many or few thereof are 70 operated together, expression controlling means to vary the degree of pressure at the striker pneumatics according as the expression controlling means are set, a spring connecting said expression controlling means 75 with said regulating pneumatic to transmit movement of the former to the latter, an operating pneumatic connected to the expression controlling means to operate the same, and humanly operable means to control the operating pneumatic.
3. In a piano playing mechanism, striker pneumatics, a source of power for actuating the striker pneumatics, a regulator for maintaining substantial uniformity of the 80 source of power upon the striker pneumatics, at all degrees of pressures whether many or few thereof are operated together, an expression controlling member having resilient connection with the regulator for 85 varying the action of the regulator and consequent pressures of the source of power with reference to the striker pneumatics, an operating pneumatic for said expression member, and a humanly controllable connection to said operating pneumatic to control the same.
4. In a piano playing mechanism, striker pneumatics, a source of power for actuating the striker pneumatics, a regulator for maintaining uniformity of pressure upon the striker pneumatics at all degrees of pressure whether few or many thereof are operated together, a pneumatic having a resilient connection with the regulator for tensioning 90 the latter, an operating pneumatic for the latter pneumatic, and a humanly controllable connection to said operating pneumatic to control the same.
5. In a piano playing mechanism, striker pneumatics, a source of power for actuating the striker pneumatics, a regulating valve, a regulating pneumatic connected to the regulating valve, an expression pneumatic, a resilient connection between the expression pneumatic and the regulating pneumatic, an operating pneumatic for the expression pneumatic and a humanly controllable connection to said operating pneumatic, to control the same.
6. In a piano playing mechanism, striker pneumatics, a source of power for actuating the striker pneumatics, a regulating valve, a regulating pneumatic having a movable board, connected to the regulating valve, an expression pneumatic having a movable board, a spring connected to the movable board of the expression pneumatic and whose tension is varied by movement of the board, a connection between said spring and

- the movable board of the regulating pneumatic, an operating pneumatic having a movable board connected to the movable board of the expression pneumatic to transmit movement to the latter, and a humanly controllable connection to the operating pneumatic, to control the same.
7. In a piano playing mechanism, striker pneumatics, a source of power for actuating the striker pneumatics, expression controlling means to control the degree of pressure at the striker pneumatics in accordance with the setting of said controlling means for high, low or intermediate pressures, respectively, pressure maintaining means for maintaining substantial uniformity of pressure for which the pressure controlling means may be set whatever number of striker pneumatics be simultaneously operated, a spring connecting said expression controlling means to said maintaining means, to transmit the action of the former to the latter, an operating pneumatic connected to the expression controlling means to operate the same, a valved connection between the source of power and the operating pneumatic, a duct to control the valve in said duct, and a humanly operable member to operate the latter valve.
8. In a piano playing mechanism, striker pneumatics, a source of power for actuating the striker pneumatics, a regulator for maintaining uniformity of pressure upon the striker pneumatics at all degrees of pressure whether few or many thereof are operated together, an expression pneumatic, a resilient connection between the expression pneumatic and regulator for tensioning the latter, an operating pneumatic for the expression pneumatic, a valved connection between the expression pneumatic and the operating pneumatic, a duct to control the valve in said connection, a valve to control said duct, and a humanly operable member to operate the latter valve.
9. In a piano playing mechanism, striker pneumatics, a source of power for actuating the striker pneumatics, a regulating valve, a regulating pneumatic connected to the regulating valve, an expression pneumatic, a resilient connection between the expression pneumatic and the regulating pneumatic, an operating pneumatic for the expression pneumatic, a valved connection between the expression pneumatic and the operating pneumatic, a duct to control the valve in said connection, a valve to control said duct, and a humanly operable member to operate the latter valve.
10. In a piano playing mechanism, striker pneumatics, a main source of power, and a regulator valve interposed between the striker pneumatics and main source of power, in combination with a first pneumatic and a second pneumatic, a connection between the first pneumatic and the regulator valve, connections under control of a record and through which the operation of the second pneumatic is controlled, a separate connection controlled by the second pneumatic and in turn controlling the first pneumatic and therethrough operating the regulator valve, non-record controlled control means and a connection between the latter control means and the second pneumatic.
11. In a piano playing mechanism, striker pneumatics, a main source of power, and a regulator valve interposed between the striker pneumatics and main source of power, in combination with a first pneumatic and a second pneumatic, a connection between the first pneumatic and the regulator valve, connections under control of a record and through which the operation of the second pneumatic is controlled, a separate and resilient connection controlled by the second pneumatic and in turn controlling the first pneumatic and therethrough operating the regulator valve, non-record controlled control means and a connection between the latter control means and the second pneumatic.
12. In a piano playing mechanism, striker pneumatics, a main source of power, and a regulator valve interposed between the striker pneumatics and main source of power, in combination with a first pneumatic and a second pneumatic, a mechanical connection between the first pneumatic and the regulator valve, pneumatic connections under control of a record and through which the operation of the second pneumatic is controlled, a separate mechanical connection controlled by the second pneumatic and in turn controlling the first pneumatic and therethrough operating the regulator valve, non-record controlled control means and a mechanical connection between the latter control means and the second pneumatic.
13. In a piano playing mechanism, striker pneumatics, a main source of power, a regulator valve interposed between the main source of power and the striker pneumatics, a pneumatic, means under control of a record and connected to said pneumatic to control the same, a non-record controlled means also connected to said pneumatic to operate the same, a regulating pneumatic free from direct connection with either of said means, a separate connection between the regulating pneumatic and the valve and a connection between the first mentioned pneumatic and the regulating pneumatic, the latter connection being operated by said first mentioned pneumatic to operate the regulating pneumatic and therethrough the regulating valve.
14. In a piano playing mechanism, striker pneumatics, a main source of power, and a regulator valve interposed between the striker pneumatics and main source of power, in combination with a first pneumatic and a second pneumatic, a connection

pneumatics, a main source of power, a regulator valve interposed between the main source of power and the striker pneumatics, a pneumatic, pneumatic means under control of a record and connected to said pneumatic to control the same by varying the tension of the air therein, a non-record controlled means mechanically connected to said pneumatic to operate the same without changing the air therein, a regulating pneumatic free from direct connection with either of said means, a separate connection between the regulating pneumatic and the valve and a connection between the first mentioned pneumatic and the regulating pneumatic, the latter connection being operated by said first mentioned pneumatic to operate the regulating pneumatic and therethrough the regulating valve.

15. In a piano playing mechanism, striker pneumatics, a main source of power, means under control of a record to variably control the tension of the air to which the striker pneumatics are subjected, including a tracker, non-opposing expression and regulating pneumatics and tracker-controlled control connections to one of said pneumatics, and also including a regulator valve having connection with both of said pneumatics; in combination with an operative-controlled controlling means free from connection to said tracker-controlled control connections and including a connection to one of said pneumatics separate from the connections between the regulator valve and said pneumatics.

16. In a piano playing mechanism, striker pneumatics, a main source of power, means under control of a record to variably control the tension of the air to which the striker pneumatics are subjected, including a regulator valve, expression and regulating pneumatics connected to said valve and tracker controlled connections to one of said pneumatics, in combination with an operative-controlled controlling means connected to said connections and operative to vent the same to thereby soften the strength of the tones, at the will of the operative.

17. In a piano playing mechanism, striker pneumatics, a main source of power, means under control of a record to variably control the tension of the air to which the striker pneumatics are subjected, including a regulator valve, an expression pneumatic, a regulating pneumatic, connections between said pneumatics and the regulator valve, a pneumatically operable valve to vent the expression pneumatic and tracker controlled control connections to said expression pneumatic and to said vent valve, in combination with an operative-controlled controlling means which taps the connection to said vent valve and is operative to vent the expres-

sion pneumatic, whereby the force of the tones predetermined by the record may be softened at the will of the operative.

18. In a piano playing mechanism, striker pneumatics, a main source of power, a regulator valve, an expression pneumatic, a connection between the expression pneumatic and the regulator valve, operative by the expression pneumatic to set the valve for any strength of tones to and including fortissimo, a tracker having expression apertures, tracker-controlled control connections between said expression apertures and the expression pneumatic, a regulating pneumatic free from separate connection with expression apertures of the tracker, an operative-controlled control means free from connection with the tracker-controlled control connections and including a connection to the expression pneumatic separate from the connection between said pneumatic and the regular valve.

19. In a piano playing mechanism, striker pneumatics, a main source of power, a regulator valve, an expression pneumatic, a connection between the expression pneumatic and the regulator valve, operative by the expression pneumatic to set the valve for any strength of tones to and including fortissimo, a tracker having expression apertures, tracker-controlled control connections between said expression apertures and the expression pneumatic, a regulating pneumatic free from separate connection with expression apertures of the tracker, an operative-controlled control means free from connection with the tracker-controlled control connections and including a power pneumatic, a connection between the power pneumatic and the expression pneumatic separate from the connection between said expression pneumatic and the regulator valve, a pneumatically operable valve to control the power pneumatic and non-record controlled means to control the tension under which the latter valve is operated.

20. In a piano playing mechanism, striker pneumatics, a main source of power and means under control of a record to variably control the tension of the air to which the striker pneumatics are subjected, including a tracker having expression apertures, non-opposing expression and regulating pneumatics, a regulator valve having connection with both of said pneumatics, and tracker-controlled control connections to the expression pneumatic from said expression apertures, operative through said expression pneumatic to set the regulator valve for any strength of tones to and including fortissimo, the regulating pneumatic being free from separate connection to expression apertures of the tracker and operated to maintain the tension for which the regulator valve has been set, in combination with an

operative-controlled control means free from connection with the tracker-controlled control connections and including a connection to the expression pneumatic separate from the connection between said pneumatic and the regulator valve.

21. In a piano playing mechanism, striker pneumatics, a source of pneumatic power for operating the same, a regulating valve, a regulating pneumatic connected to the valve, an expression pneumatic connected to the valve through said regulating pneumatic, a record-controlled control means connected to the expression pneumatic and operative thereon to set the regulating valve for tones of varying intensities from pianissimo to and including fortissimo, and a non-record controlled control means also connected to said expression pneumatic and operative to vent the same at the will of the operator to thereby lessen the intensity of the tones effected under control of the record-controlled control means operated alone.
22. In a piano playing mechanism, striker pneumatics, a source of pneumatic power for operating the same, a regulating valve, a regulating pneumatic and an expression pneumatic both connected to the valve, a record controlled control means connected to one of said pneumatics and operative thereon to set the regulating valve for tones of varying intensities from pianissimo to and including fortissimo, and a plurality of separate non-record controlled control means, both connected to the latter pneumatic and operative thereon the one to adjust the valve for a stronger tone and the other to reduce the tension of the air in the pneumatic to thereby adjust the valve for a weaker tone.
23. In a piano playing mechanism, striker pneumatics, a source of power for actuating the same, a regulating valve, and mechanism

to set the valve in various positions selectively in accord with the intensity of the tones to be produced and to maintain the corresponding tensions regardless of the number of striker pneumatics simultaneously operated, said mechanism including an expression pneumatic, record controlled means operated to variably collapse said pneumatic to set the valve in selected positions predetermined by the record, and a nonrecord controlled venting means operatively related to the pneumatic and operative to vent said pneumatic to change such predetermined setting of the valve at the will of the operative.

24. In a piano playing mechanism, striker pneumatics, a source of power for actuating the same, a regulating valve, pressure maintaining means, an expression controlling pneumatic, record controlled means for collapsing said pneumatic, and a non-record controlled connection to the pneumatic for reducing at will the tension of the air therein brought about by the record controlled means to thereby modify the action of the record controlled means upon the valve.

25. In a piano playing mechanism, striker pneumatics, a source of power for actuating the same, a regulating valve, pressure maintaining means, an expression controlling pneumatic, record controlled means for increasing the tension of the air in said expression controlling pneumatic, an operating pneumatic, a connection between the same and the expression controlling pneumatic to operate the latter, a non-record control means for controlling the operating pneumatic, a venting means for the expression pneumatic, and non-record controlled means for controlling the venting means to modify the effect of the operating pneumatic.

In testimony whereof I affix my signature.
TOLBERT F. CHEEK.
